(57) CLAIM

The ornamental design for a car cover, as shown and described.

DESCRIPTION

FIG. 1 is a front perspective view of a car cover showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is another perspective view thereof, showing the new design in a state of use; and,

FIG. 9 is an enlarged view of the car cover taken from the circle part in FIG. 4.

The broken lines in FIGS. 4 and 9 illustrate the periphery of the enlarged view of the car cover and form no part of the claimed design.

1 Claim, 9 Drawing Sheets
